US0D1112994S

(12) **United States Design Patent** (10) **Patent No.:** **US D1,112,994 S**
(45) **Date of Patent:** **** Feb. 10, 2026**

(54) **ANTI BARK COLLAR DEVICE**

(71) Applicant: **Shenzhen TIZE Technology Co., LTD.**, Shenzhen (CN)

(72) Inventor: **Jian Wen**, Shenzhen (CN)

(73) Assignee: **Shenzhen TIZE Technology Co., LTD.**, Shenzhen (CN)

(**) Term: **15 Years**

(21) Appl. No.: **29/919,872**

(22) Filed: **Dec. 6, 2023**

(30) **Foreign Application Priority Data**

Aug. 11, 2023 (CN) 202330512623.7

(51) **LOC (15) Cl.** **30-99**

(52) **U.S. Cl.**

USPC **D30/199; D10/104.1**

(58) **Field of Classification Search**

(57) **CLAIM**

The ornamental design for an anti bark collar device as shown and described.

DESCRIPTION

FIG. 1 is a front, right and top perspective view of an anti bark collar device, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the anti bark collar device that form no part of the claimed design.

1 Claim, 8 Drawing Sheets
